FONT-SELECTING MECHANISM FOR MONOLINE COMPOSING-MACHINES.

978,108.

Specification of Letters Patent.

Patented Dec. 6, 1910.

Application filed July 6, 1909. Serial No. 506,087.

To all whom it may concern:

Be it known that I, WILLIAM E. BERTRAM, a citizen of the United States, residing at Brooklyn, in the county of Kings and State 5 of New York, have invented new and useful Improvements in Font-Selecting Mechanism for Monoline Composing-Machines, of which the following is a specification.

The present invention relates to improvements in composing machines and more particularly to the monoline type wherein the matrices are stored in a magazine and are brought to the assembling point by the manipulation of the keyboard, and it has for 10 its object to provide means whereby a plurality of fonts of matrices may be combined in the same machine and matrices from any one selecting font may be quickly and easily brought into use from the same keyboard, 15 the capacity of the machine being thereby materially increased and the printed matter may be set up in type of different styles without requiring the use of one or more separate machines or the interchanging of 20 matrices.

More specifically, the invention provides simple and efficient font selecting devices which are interposed between the detent levers and the detents whereby matrices 25 from any one of a plurality of fonts may be readily brought into use from the same keyboard.

To these and other ends, the invention consists in certain improvements, and combinations and arrangements of parts, all as 30 will be hereinafter more fully described, the novel features being pointed out particularly in the claims at the end of the specification.

40 In the accompanying drawing: Figure 1 is a perspective view showing the detents which control the matrix delivery gates, the detent levers and the font selecting devices; Figs. 2 and 3 are perspective views showing 45 the font controlling device in two different positions whereby matrices from two different fonts may be brought into use; Fig. 4 is a perspective view showing a font controlling device modified so as to accommodate three different fonts of matrices which may all be contained in the same machine, and Fig. 5 represents a vertical section 50 through the rear portions of the detents and the matrix delivery gates.

Similar parts are designated by the same 55 reference characters in the several views.

In the accompanying drawing, I have shown certain embodiments of the invention and these embodiments are especially applicable to the well known monoline type of 60 composing and casting machines such as disclosed in Letters Patent, No. 605,141 granted June 7, 1898. It will be understood, however, that the specific constructions shown and to be hereinafter described are given as 65 examples of the invention and the invention is not limited in these respects, as certain modifications and changes may be made therein in order that the invention may be applied to the best advantage in each particular case.

In the present instance, 1 designates the usual reciprocatory matrix delivery gate and, according to the present embodiment of the invention, there will be seven gates 75 for each font of matrices. In that form of the invention shown in Figs. 1-3 inclusive, provision is made for the use of two fonts of matrices which may be combined in the same machine and controlled by the same 80 keyboard. There will consequently be fourteen matrix delivery gates, and these matrix delivery gates are controlled in their delivery movements by detents 2 which are preferably individual to the various gates; in 85 other words, fourteen detents are shown for controlling the delivery movements of the corresponding number of gates. These detents are preferably arranged in a row and in alinement, they being preferably pivoted 90 upon a common pivot pin 3 which pin is supported by a suitable bracket 4, and the detents are provided with individual downwardly projecting fingers 5 through the medium of which the detents are operated to 95 release their respective gates.

According to the present invention, the font controlling and selecting devices are interposed between the detents and the detent levers which will be hereinafter described 100 and, in the present instance, these selecting devices consist of a series of pawls 6 which are preferably arranged in a row and pivoted upon a common pintle 7, this pintle in turn being mounted in a carrier 8 which in 105 turn is shiftable on a support 9. This carrier in the instance shown is shiftable in a direction substantially longitudinally of the

detents, and any suitable means may be provided for guiding the carrier in its movement. In the present instance, the carrier rests upon the support 9 and pins 10 on the support rest in slots 11 formed in the carrier.

According to the present embodiment of the invention, I provide a single series of detent levers 12 which preferably correspond in number to the number of delivery gates and detents for one font of matrices, and the upper ends of these detent levers are preferably arranged directly beneath or in register with the detents forming one series, 15 a pin or projection 13 extending laterally from one side of each detent lever. These detent levers are preferably arranged in a row and pivoted on a common axis 14, the latter being mounted in a support 15 which 20 support may be conveniently attached to the support 9. The detent levers may be as usual connected to the keyboard mechanism by links 16, these links in turn being connected through the rods 17 to the reciprocatory draw bars 18, the draw bars being connected to the key levers.

Any suitable means may be provided for shifting the font selecting and detent controlling devices. In the present instance, I 30 have shown for example a lever 19 the end of which may be located within convenient reach of the operator, and this lever is pivoted or fulcrumed at 20 to the support 9, the end of the lever being forked as at 21 and is 35 arranged to coöperate with a pin or projection 22 formed on a lug 23, this lug being formed on or attached to the shiftable carrier.

The font selecting and detent controlling pawls 6 in that form of the invention shown in Figs. 1-3 inclusive, are capable of operating a series of detents for one or another of two fonts of matrices, each pawl in the present instance being provided with a 40 laterally offset detent-engaging portion 6^a which rests above the respective detent lever and beneath the depending finger 5 of a detent of one series while a clearance space is formed beside this portion 6^a which will 45 permit a lifting movement of the pawl to trip the detent of one series and avoiding tripping the next detent of a second series. When the carrier 8 is shifted into a forward position, this portion 6^a is in operative 50 position. When, however, the carrier 8 is shifted rearwardly or into a second position, the detent tripping portion 6^a is pushed clear of the depending finger 5 of one detent and the body portion of the pawl is 55 carried into a position to rest upon the laterally extending pin or projection 13 of the detent lever while its upper surface is adapted to rest beneath the depending finger 5 of the detent of a second series, as shown in 60 Fig. 3. By operating the detent lever while

the pawl 6 is in this second position, obviously, the detent of the second series will be tripped while that of the first series will remain in locked position.

In Fig. 4, I have shown a font selecting 70 device which is capable of operating the gate controlling detents of any one of three series, one series of detents being provided for each font of matrices. In this construction, the pawl 6 is provided with a body portion which serves to trip a detent of one series, and two laterally stepped or offset tripping portions 7^a and 7^b which are arranged in diagonal relation. The carrier for the pawls in this latter construction will be capable of occupying three different positions and while occupying any one of these three different positions, the gate controlling detent for the desired font will be in position to be tripped while the two detents of the 80 remaining two series will be unaffected by a lifting of the pawl and will, therefore, remain locked.

The font selecting devices which in the present instance are interposed between the 90 gate controlling detents and the detent levers serve in effect as filling-in pieces and by mounting these selecting devices whereby they may be adjusted in a direction longitudinally with respect to the detents, it is 95 possible to use three or more fonts in the same machine owing to the clearance or greater range of movement available with respect to the gate controlling detents.

I claim as my invention:

1. In a composing machine, the combination of a plurality of series of gates for controlling the delivery of matrices of different fonts, one series of gates for one font being arranged in alternating relation with 105 the series for another font, a series of devices controlling the delivery movements of said gates, a series of releasing devices for said gate controlling devices, and font selecting devices interposed between said gate controlling and releasing devices and capable of occupying different positions relatively to the gate controlling devices, each selecting device having relatively offset portions capable of being positioned to coöperate with and trip the gate controlling devices for one or another font.

2. In a composing machine, the combination of a plurality of series of gates for controlling the delivery of matrices of different 120 fonts, one series of gates for one font being arranged in alternating relation with the series for another font, a series of devices for controlling the delivery movements of said gates, a series of releasing devices for said gate controlling devices, and font selecting devices interposed between said gate controlling and releasing devices and adjustable relatively to the gate controlling devices, each selecting device having later- 130

ally stepped tripping portions capable of being positioned to coöperate with and trip the gate controlling devices for one or another font.

5. In a composing machine, the combination of a plurality of series of gates for controlling the delivery of matrices of different fonts, a series of detents for controlling the delivery movements of said gates, one series 10 of gates and detents for one font being arranged in alternating relation to the gates and detents of another series and for another font, a series of detent levers for tripping said detents, and font selecting devices 15 shiftable in a direction parallel to the plane of movement of the detents and having differently positioned detent tripping portions capable of being positioned to coöperate with and trip the detents of one or another 20 series.

4. In a composing machine, the combination of a plurality of series of gates for controlling the delivery of matrices of different fonts, a plurality of series of detents for controlling the delivery movements of said gates, a series of detent levers, and font selecting means interposed between said detents and the detent levers and embodying pawls having detent tripping portions arranged in stepped relation, the relation between said pawls and detents being variable whereby the detents of any one series may be tripped by the detent levers.

5. In a composing machine, the combination of a plurality of series of gates for controlling the delivery of matrices of different fonts, detents individual to said gates for controlling the delivery movements thereof, a series of detent levers, and font selecting 35 means interposed between said detents and detent levers, said selecting means embodying a series of pawls, each pawl having a plurality of detent tripping portions arranged in laterally stepped relation, the

pawls being shiftable longitudinally whereby the series of detent levers may be operatively associated with one or another series of detents.

6. In a composing machine, the combination of a plurality of series of gates for controlling the delivery of matrices of different fonts, a plurality of series of detents for controlling the movements of said gates, one series of gates and detents for one font alternating with another series for a different 50 font, a set of detent levers, and filling-in pieces interposed between said detents and the detent levers and adjustable relatively to the detents, each filling-in piece having differently located portions capable of being 55 positioned to operate detents for different fonts whereby a detent for one or another of a plurality of fonts may be released.

7. In a monoline composing machine, the combination of a plurality of series of gates for controlling the delivery of matrices of different fonts, corresponding series of detents for controlling the movements of said gates and arranged in a row, the detents for one font of matrices and forming one series 60 alternating with another series of detents for a different font of matrices, a carrier shiftable in a direction transversely of said row of detents, a set of selecting devices pivotally connected to said carrier and shiftable 65 therewith, each selecting device having relatively offset portions to be operatively positioned relatively to a detent of one or another series when said carrier is shifted, and a set of releasing devices coöperative with 70 the selecting devices for actuating them.

In testimony whereof I have hereunto set my hand in presence of two subscribing witnesses.

WILLIAM E. BERTRAM.
